[57] CLAIM

The ornamental design for a postoperative back pillow support, as shown and described.

DESCRIPTION

FIG. 1 is an environmental perspective view of a postoperative back pillow support showing my new design; FIG. 2 is a front elevational view with the rear elevational view being a mirror image thereof; FIG. 3 is a right side elevational view with the left side being a mirror image thereof; FIG. 4 is a top view thereof; and, FIG. 5 is a bottom view thereof.
The broken line showing of a chair in FIG. 1 is for illustrative purposes only and forms no part of the claimed design.

FIG. 1

FIG. 3

FIG. 2

FIG. 4

FIG. 5
